(57) **CLAIM**

The ornamental design for a suction cup mount, as shown and described.

DESCRIPTION

FIG. 1 is a top and left side perspective view of a suction cup mount in a folded and locked and unrotated configuration showing our new design;

FIG. 2 is a top and right side perspective view thereof;

FIG. 3 is top plan view thereof;

FIG. 4 is a bottom plan view thereof;

FIG. 5 is a rear elevational view thereof;

FIG. 6 is a front elevational view thereof;

FIG. 7 is a left side elevational view thereof;

FIG. 8 is a right side elevational view thereof; and

FIG. 9 is a top and and left side perspective view of a suction cup mount in an unfolded and locked and unrotated configuration.

FIG. 10 is top and right side perspective view thereof.

FIG. 11 is a top plan view thereof.

FIG. 12 is a front elevational view thereof.

FIG. 13 is right side elevational view thereof.

FIG. 14 is right side elevational view of a suction cup mount in an unfolded and unlocked configuration.

FIG. 15 is a top and right side perspective view thereof.

FIG. 16 is top and left side perspective view of a suction cup mount in a folded and locked and rotated configuration;

FIG. 17 is a top plan view thereof; and,

FIG. 18 is a top and right side perspective view of a suction cup mount in an unfolded and locked and rotated configuration.

The broken lines in the drawings showing portions of the suction cup mount are included for the purpose of illustrating environmental structure and form no part of the claimed design.
